US0D1011719S

(12) **United States Design Patent** (10) **Patent No.:** **US D1,011,719 S**
(45) **Date of Patent:** **** Jan. 23, 2024**

(54) **SHOE SOLE**

(71) Applicant: **SHENZHEN KEKELU ENVIRONMENTAL PROTECTION TECHNOLOGY CO. LTD**, Shenzhen (CN)

(72) Inventor: **Lu Guo**, Shenzhen (CN)

(73) Assignee: **SHENZHEN KEKELU ENVIRONMENTAL PROTECTION TECHNOLOGY CO. LTD**, Shenzhen (CN)

(**) Term: **15 Years**

(21) Appl. No.: **29/837,972**

(22) Filed: **May 10, 2022**

(51) LOC (14) Cl. **02-04**

(52) U.S. Cl.

USPC **D2/952**; D2/947; D2/951; D2/953; D2/954; D2/955; D2/960
